TRAVELING CASE

Aleck Knell, Los Angeles, Calif.

Application June 19, 1950, Serial No. 10,634

Term of patent 14 years

(Cl. D87—5)

To all whom it may concern:

Be it known that I, Aleck Knell, a citizen of the United States, residing at 106 South Vista Street, in the county of Los Angeles and State of California, have invented a new, original, and ornamental Design for Traveling Cases, of which the following is a specification, reference being had to the accompanying drawing, forming part thereof.

Fig. 1 is a front perspective view of a traveling case embodying my new design;

Fig. 2 is a similar perspective view illustrating the case in an open position;

Fig. 3 is a rear perspective view of the traveling case; and

Fig. 4 is a bottom plan view thereof.

The dominant features of the design are shown in full lines.

I claim:

The ornamental design for a traveling case, substantially as shown and described.

ALECK KNELL.
